US0D1032429S

(12) **United States Design Patent** (10) Patent No.: **US D1,032,429 S**
(45) Date of Patent: ** Jun. 25, 2024

(54) **VEHICLE BONNET**
(71) Applicant: **Polaris Industries Inc.**, Medina, MN (US)
(72) Inventors: **Ian M. Dunn**, Chanhassen, MN (US); **Garth H. Bracy**, Robbinsdale, MN (US); **James E. Rogala**, Byron Center, MI (US); **James A J Holroyd**, Stillwater, MN (US); **Bret H. RempelEwert**, Shafer, MN (US); **John A. Zvonek**, Livonia, MI (US)
(73) Assignee: **Polaris Industries Inc.**, Medina, MN (US)

(**) Term: **15 Years**

(21) Appl. No.: **35/002,189**

(22) Filed: **Dec. 6, 2021**

(80) **Hague Agreement Data**

Int. Filing Date: **Dec. 6, 2021**

Int. Reg. No.: **DM/219707**

Int. Reg. Date: **Dec. 6, 2021**

Int. Reg. Pub. Date: **Apr. 1, 2022**

(51) **LOC (14) Cl.** **12-08**

(52) **U.S. Cl.**

USPC **D12/173**

(58) **Field of Classification Search**

USPC D12/14, 82, 86, 87, 89, 90, 91, 92, 93, D12/96, 97, 98, 99, 164, 167, 169, 107, D12/110, 111, 113, 114, 170, 171, 172, D12/173, 181, 184, 185, 190, 192, 196; D21/533, 548, 552, 561

CLAIM

The ornamental design for a vehicle bonnet, as shown and described.

DESCRIPTION

1. Vehicle bonnet

1.1 : Perspective

1.2 : Front

1.3 : Back

1.4 : Left

1.5 : Right

1.6 : Top

1.7 : Bottom

The evenly dashed broken lines shown in the drawings illustrate portions of the vehicle bonnet and forms no part of the claimed design. The dot-dash lines illustrate boundaries of the design and forms no part of the claimed design.

1 Claim, 5 Drawing Sheets
